UNITED STATES PATENT OFFICE.

J. WILLIAM C. PETERS, OF CHICAGO, ILLINOIS.

IMPROVEMENT IN WIRE FABRICS.

Specification forming part of Letters Patent No. 124,286, dated March 5, 1872.

To all whom it may concern:

Be it known that I, J. WILLIAM C. PETERS, of Chicago, in the county of Cook and State of Illinois, have invented a certain new and useful Improvement in Woven-Wire Mattresses; and I do hereby declare the following to be a full, clear, and exact description thereof, which will enable others skilled in the art to which my invention appertains to make and use the same, reference being had to the accompanying drawing forming a part of this specification, in which the figure there shown represents a top or plan view of a woven-wire fabric embodying my improvement, similar letters of reference indicating like parts.

My invention relates to woven-wire fabric such as is usually employed in the manufacture of mattresses; and it consists in combining or interweaving therewith one or more metallic bands, preferably coiled in the form of a spiral, for the purpose of strengthening the fabric, as will be hereinafter more fully described.

General Description.

B B are metallic bands, made of steel or similar metal, and their surfaces may be flat or slightly oval. These bands are preferably coiled in the form of a spiral in such a manner as to leave a sufficient space between each coil for the interweaving of the wire fabric, in-

to which the bands may be introduced. These bands may be of any desired width and thickness, and their spirals may be of any suitable diameter. The bands may also be formed of double spirals, as shown at B C, or more than two spirals may be so used, if desired. A A are portions of woven-wire fabric like that usually employed in the construction of mattresses and for similar purposes, and the bands may be placed at any suitable distances apart, so as to strengthen such parts of the fabric as are subject to the greatest strain.

I am aware that several wires coiled together have been used for similar purposes; but I do not claim such. My improved bands secure greater strength and elasticity, and are much more readily made and applied.

Claim.

Having thus described my invention, what I claim, and desire to secure by Letters Patent, is—

The combination of the bands B, one or more, with woven-wire fabric, substantially as and for the purpose shown and described.
